(57) **CLAIM**

The ornamental design for a headlight for a motor vehicle, as shown and described.

DESCRIPTION

FIG. 1 is a perspective view of a headlight for a motor vehicle; FIG. 2 is a front elevation view of the headlight; FIG. 3 is a top elevation view of the headlight; and, FIG. 4 is an elevation view from the right side of the headlight. The portions of the headlight that are encircled by broken lines are for illustration purposes only and form no part of the claimed design.
